UNITED STATES PATENT OFFICE.

FRANK H. FAY, OF HOXIE, KANSAS.

TWO-BOLT DOOR-LOCK.

No. 804,837.

Specification of Letters Patent.

Patented Nov. 21, 1905.

Application filed September 29, 1904. Serial No. 226,540.

To all whom it may concern:

Be it known that I, FRANK H. FAY, a citizen of the United States, residing at Hoxie, in the county of Sheridan and State of Kansas, have 5 invented certain new and useful Improvements in Two-Bolt Door-Locks, of which the following is a specification.

The primary object of this invention is the provision of a lock of novel construction specifically designed for doors and which is free of springs and capable of utilizing both the latch and the lock-bolts for securing of the door, the latch being held by means of a key or like part inserted in the lock and serving in turn 15 to prevent operation of the lock-bolt by the key.

For a full description of the invention and the merits thereof and also to acquire a knowledge of the details of construction of the means 20 for effecting the result reference is to be had to the following description and accompanying drawings.

While the essential and characteristic features of the invention are susceptible of modification, still the preferred embodiment of the invention is illustrated in the accompanying drawings, in which—

Figure 1 is a front view of a lock embodying the invention, the face-plate being omitted. Fig. 2 is a view similar to Fig. 1, showing the lock-bolt projected and the key inserted for securing the latch. Fig. 3 is a transverse section of the lock on the line $\alpha\alpha$ of Fig. 1. Fig. 4 is a perspective view of the 35 pivoted latch-actuator. Fig. 5 is a detail perspective view of the lock-bolt and the tumbler coöperating therewith, the parts being separated. Fig. 6 is a detail perspective view of the latch. Fig. 7 is a detail perspective 40 view of the knob-operated tumbler.

Corresponding and like parts are referred to in the following description and indicated in all the views of the drawings by the same reference characters.

The invention may be adapted to the different types of locks provided with knob-operated latches. The casing for inclosing the operating parts is of the accustomed construction, comprising a box 1 and face-plate 2, the latter being secured to the box portion by any suitable fastening means. The latch-bolt is gravity-actuated and comprises the latch 3 and pivoted latch-actuator 4. The pivoted latch-actuator comprises the horizontal weight-bar 5, upright 6, horizontal arm 7, and vertical arm 8. The portion of the upright 6 adja-

cent to the weight-bar 5 is reduced upon opposite sides to receive the spaced members of the latch, which are pivoted thereto by means of the pin 9. The latch-actuator is pivoted 60 at its upper forward corner to the casing, as indicated at 10, thereby throwing the preponderance of weight in the rear of the upright 6, with the result that the latch 3 is normally projected. When the latch is repressed 65 or moved inward to permit opening or closing of the door, its actuator turns upon the pivot-support 10, the weight-bar 5 moving inward and upward, as will be readily understood. The knob-operated tumbler 11 has one arm 12 arranged in the path of the horizontal arm 7 and its other arm 13 overlapping the arm 8 and adapted to engage with a shoulder 14, formed near the upper end of said arm. The arm 13 has a pendent portion from which projects a stud 70 75 15, so as to engage with the inner edge of the vertical arm 8 and move the latch-actuator when the tumbler is turned in one direction, the arm 12 serving a similar purpose by engagement with the horizontal arm 7 when the 80 tumbler is turned in the opposite direction. The latch 3 is reversible to admit of the lock being used upon either a right-hand or a left-hand door. This is effected by removing the pin 9 and turning the latch and replacing the 85 pin.

The lock-bolt 16 has a longitudinal slot 17, through which is passed a pin or stud 18, forming a part of or applied to the casing. The tumbler 19, coöperating with the lock-bolt, is pivotally mounted upon the pin or stud 18 and is weighted at 20. An extension 21 projects laterally from the tumbler, so as to overlap the inner portion of the lock-bolt and engage upon either side of a stop 22 thereof, 95 so as to hold the lock-bolt either projected or withdrawn. When operating the lock-bolt by means of the key, the tumbler is lifted to move the extension 21 out of the path of the stop 22, thereby admitting of a free sliding 100 movement of the lock-bolt when shot either inward or outward. As the lock-bolt reaches the limit of its movement in either direction the weighted end of the tumbler 19 descends and causes the extension 21 to engage with the 105 stop 22, thereby fixing the position of the lock-bolt in the manner well understood.

The lock-casing is provided with a keyhole 23 adjacent to the inner end of the weight-bar 5 of the pivoted latch-actuator, so that upon 110 the introduction of a key 24 into said key-hole the latch-actuator is prevented from op-

eration, thereby admitting of the latch acting in the capacity of a lock-bolt.

It is to be understood that the keyhole 23 may be arranged in any position to admit of 5 the key 24 or like part obstructing the movement of the latch-actuator, whereby the latter may be utilized at will in the capacity of a lock-bolt.

It is proposed to utilize the latch-actuator 10 as lock means for the tumbler, thereby preventing opening of the lock at stated times. For this purpose the latch-actuator is provided with an extension 25, projected so as to extend into the path of the tumbler to prevent 15 its operation without moving the latch-actuator. As indicated, the extension 25 projects into the path of the lateral extension 21 of the tumbler. When the tumbler is lifted by means of the key in the well-known manner, the latch-actuator is correspondingly moved. Obviously when the key or like part 20 24 is in position to prevent movement of the latch-actuator the tumbler 19 cannot be moved. It therefore follows that the part 24 25 secures both the latch and the lock-bolt against movement when introduced into the lock-casing.

A pin 26 projects from the lock-case and forms a stop to limit the upward movement 30 of the tumbler and prevent opening of the lock by means of a key having the slot in its web or bit too shallow.

Having thus described the invention, what is claimed as new is—

35 1. In a lock, the combination of a latch-ac-

tuator comprising a horizontal weight member, an upright at one end of said weight member having opposite side portions reduced, a vertical arm at the opposite end of the weight member formed with a lateral shoulder, a 40 horizontal arm extended from the upper portion of said upright, a latch comprising spaced portions embracing a reduced part of the aforesaid upright and pivotally connected thereto and adapted to be reversed, means for 45 pivotally supporting the latch-actuator approximately at the angle formed between the upright and horizontal arm, and a knob-operated tumbler having opposite arms arranged to coöperate with corresponding arms of the 50 latch-actuator, and one of said arms having a lateral stud to engage with the aforesaid vertical arm, substantially as described.

2. In a lock, the combination of a pivoted latch-bolt having an extension, a lock-bolt 55 provided with a stop, a tumbler having an extension coöperating with the stop of the lock-bolt and with the extension of the latch-bolt for operating the latter at each actuation of said tumbler and lock-bolt, and a key for 60 securing the latch-bolt by direct contact therewith and at the same time preventing movement of the lock-bolt and its tumbler, substantially as set forth.

In testimony whereof I affix my signature in 65 presence of two witnesses.

FRANK H. FAY. [L. S.]
